UNITED STATES PATENT OFFICE.

SAMUEL KING, OF HARRISBURG, PENNSYLVANIA.

DESIGN FOR A SHELF FOR SCALE-WEIGHTS.

SPECIFICATION forming part of Design No. 24,780, dated October 22, 1895.

Application filed August 1, 1895. Serial No. 557,907. Term of patent 14 years.

To all whom it may concern:

Be it known that I, SAMUEL KING, a citizen of the United States, residing at Harrisburg, in the county of Dauphin and State of Pennsylvania, have invented a certain new and original Design for a Shelf for Holding Scale-Weights; and I do declare the following to be a full, clear, and exact description of the invention.

10 My invention relates to a new design for a shelf for scale-weights.

The design consists of a shelf of the configuration and ornamentation shown in the accompanying drawing, in which I have represented the shelf in perspective.

15 The leading features of my design are the base 1, having parallel straight sides 2, rounded ends 3, and diamond-shaped apertures 4, the walls of which are corrugated or fluted. Extending vertically from one end of

the base is a vertical arm 5, the ends of which are flared laterally on a curve. A semicircular shelf 6 is located at the upper end of the arm and has at its outer edge and at its ends a marginal rib 7. This shelf has leaf-shaped 25 ornamental apertures 8.

A shelf thus constructed is very ornamental and pleasing to the eye and will be found very convenient for the purpose for which it is designed.

30 What I claim is—

The design for a shelf for scale weights, as herein shown and described.

In testimony whereof I affix my signature in presence of two witnesses.

SAMUEL KING.
